UNITED STATES PATENT OFFICE.

REISSUED

FRANK S. CHANCE, OF INDIANAPOLIS, INDIANA.

PICTURE-DISPLAYING DEVICE.

SPECIFICATION forming part of Letters Patent No. 591,452, dated October 12, 1897.

Application filed April 15, 1897. Serial No. 632,255. (No model.)

To all whom it may concern:

Be it known that I, FRANK S. CHANCE, a citizen of the United States, residing at Indianapolis, in the county of Marion and State of Indiana, have invented certain new and useful Improvements in Picture-Displaying Devices; and I do declare the following to be a full, clear, and exact description of the invention, such as will enable others skilled in the art to which it appertains to make and use the same, reference being had to the accompanying drawings, and to the figures of reference marked thereon, which form a part of this specification.

15 My invention relates to an improved device for consecutively displaying a series of pictures with sufficient rapidity to give to the figures in the pictures the appearance of moving.

The objects of my invention are to provide 20 a device of that class that will be simple in operation, cheap of manufacture, and adapted to be made of such size as to permit of its being carried in the pocket.

A further object is to provide an inexpensive means, in a device of the class described, 25 for securing the sheets evenly upon the central roller or shaft, and in such a manner as to give the desired effect when they are rotated, a means for rotating said central shaft, 30 and a means for causing each succeeding picture to instantaneously take the place of the preceding picture and to allow each picture, as it appears, to stop long enough for the image to become fixed upon the retina of the eye.

35 With these objects in view my invention consists in the construction and combination of parts shown in the accompanying drawings, described in the following specification, and more particularly pointed out in the 40 claims.

In the drawings, Figure 1 is a perspective view of my device. Fig. 2 is a sectional view taken on the line $y-y$ of Fig. 3. Fig. 3 is a sectional view taken on the line $x-x$ of Fig. 2; 45 and Fig. 4 is a fragmentary view illustrating the method of securing the sheets to the fabric, said fabric in turn secured upon the shaft.

1 is the case.
2 is the crank.
3 is the central shaft.
4 are the picture-sheets.
5 is the fabric upon which the sheets are

secured, and 6 is a shoulder to engage the outer edges of the sheets 4.

The case 1 may be made of any desired 55 outline consistent with its purpose, and is provided with the opening 14 in its upper edge, preferably V-shaped, as seen from the sides, through which the pictures are viewed as they consecutively appear. The central 60 shaft or roller 3 fits between the sides of the case 1 and has a central opening 7 throughout its length, through which the axle 8, which is a continuation of and integral with the crank 2, is adapted to pass. The shaft 3 may 65 be of wood or other suitable material and the fabric 5 is rolled around said shaft and secured with glue or like adhesive substance. The sheets 4 to be attached to the fabric are spread out, with the ends of each succeeding 70 sheet overlapping the one beneath it, as shown in Fig. 4, thereby exposing the edge and a short section of the side of each sheet. Glue or other adhesive substance is then applied to the exposed portions 9 of the sides and 75 naturally fills up the slight depression caused by the thickness of each succeeding sheet. This glue is indicated by the black line 10 between the fabric 5 and sheets 4 in Fig. 4. The fabric 5, which has previously been cut 80 to the proper width and length, is then placed upon the glued surface of the sheets and pressed, so it will adhere firmly. The fabric is then wrapped around the shaft 3, as above described. This wrapping causes the outer 85 edges of the sheets 4 to spread out, as in Fig. 2. The axle 8 is journaled in the case 1 through openings 11. Said openings 11 are located on a line between the center of the case 1 and the point of the shoulder 6, slightly above 90 said center, as may be seen in Figs. 1, 2, and 3 of the drawings. It will be observed that this has the effect of causing the outer edges of the sheets 4 to come in contact with the inside edge of the case 2 at 12, and as the 95 shaft 3 is rotated the sheets are curved backward, by reason of said contact, until they come in contact with the shoulder 6, when the curve is increased, thereby causing the sheets to spring forward with great rapidity 100 when they pass the shoulder 6, and as they strike the rear edge 13 of the V-shaped opening 14 there is a short pause in the movement, just sufficient to allow the image to

become fixed in the retina of the eye, when the next sheet springs forward and takes its place. This being repeated as the entire series of pictures or views printed upon the 5 sheets 4 pass before the opening in the case 1 give to the pictures the appearance of movement, as of walking, dancing, &c.

It will be understood that the series of views displayed in the case will be of the 10 same object or objects in varied attitudes in order to give the above-described effects.

The device described may be made very cheaply by forming the case 1 of pasteboard and printing the pictures upon the sheets 4 15 from printing-plates. The method of securing the sheets 4 upon the roller 3 is inexpensive, yet places said sheets evenly in the position shown, which is essential to the proper working of the device. The axle 8 is fixed immovably in the opening 7 in the shaft 3. Therefore the shaft is rotated as the crank 2, which is integral with the axle 8, is turned. The instantaneous movement of the sheets carrying the pictures is effected by the shoulder 25 6 and by having the axle 8 mounted out of the center, as shown. Each sheet as it passes the shoulder 6 springs against the edge 13 so quickly that the eye cannot follow it, but its short stop or dwell as it strikes the 30 edge 13 enables the eye to catch the image and retain it until the next view is presented. In operation it is only necessary to turn the crank 2 slowly and evenly, when the effects above described will be attained.

35 I am aware that it is not new to present a series of views consecutively in order to give the moving effect, but I am not aware that the effects described have ever been produced by the means and in the manner employed in my device.

Having described my invention, what I claim, and desire to secure by Letters Patent of the United States, is—

1. As an article of manufacture, a picture-displaying device having a case 1, provided with a V-shaped opening in the top thereof, the roller 3, having a fabric 5, to which are adhesively attached sheets 4, removably fixed thereon, said roller journaled in said case 1

50 by means of the axle 8, said axle being positioned slightly out of the center of said case for the purpose of bringing the outer edges of the sheets 4 into more decided contact with the shoulder 6, projecting inwardly from the front edge of the V-shaped opening in 55 said case, substantially as set forth.

2. In a picture-displaying device of the class described, the combination of the case 1, having the V-shaped top opening 14, and the shoulder 6, projecting inwardly from the front 60 edge of said V-shaped opening, with the roller 3, mounted upon the axle 8, adapted to be rotated by the crank 2, said axle 8, journaled in the case 1, through openings 11, 65 said openings located slightly above the center on a line with said shoulder 6, and the sheets secured to the fabric 5, by means of adhesive substance, in the manner described, said fabric being in turn secured upon the roller 3, as set forth. 70

3. In a picture-displaying device, the combination of the case 1, provided with the inwardly-projecting shoulder 6 secured inside the case near the front edge of the opening formed therein, and having the V-shaped 75 opening in the top thereof, with a series of sheets 4 mounted upon a fabric 5, and said fabric fixedly secured upon a roller 3, said roller 3 mounted upon an axle 8 fixed in the case 1, upon a line between the center of said 80 case and the point of the shoulder 6, as shown and described.

4. The combination in a picture-displaying device of the class described, of the case 1, having the V-shaped opening 14 in the upper part thereof, the inner depending shoulder 6, and the axle 8 mounted in said case 1, slightly above the center on a line with said shoulder 6, with the roller 3 fixedly mounted upon the axle 8, and having the fabric 5 carrying the adhesively-mounted sheets 4 fixedly secured thereon, as set forth. 85 90

In testimony whereof I affix my signature in presence of two witnesses.

FRANK S. CHANCE.
